UNITED STATES PATENT OFFICE.

JAMES C. TATE, OF KYGER, OHIO.

DESIGN FOR A PANEL FOR FIRE-ESCAPE LADDERS.

SPECIFICATION forming part of Design No. 32,036, dated December 26, 1899.

Application filed November 15, 1899. Serial No. 737,129. Term of patent 7 years.

to all whom it may concern:

Be it known that I, JAMES C. TATE, a citizen of the United States, residing at Kyger, in the county of Gallia and State of Ohio, have invented and produced a new and original Design 5 for Panels for Fire-Escape Ladders, of which the following is a specification.

My invention relates to designs in panels for fire-escape ladders, and the essential feature of my novel design is a panel consisting of single rods forming the rungs and twisted wires forming the side pieces, said rungs and side pieces being connected by loops formed integrally with said parts and interlocked, as 5 shown in the accompanying drawing, which forms a part of this specification, and in which the figure represents a perspective view of my new design.

In said figure of the drawing the numeral 1 designates the rungs of the panel, the lower one of which is formed of a single plain rod having its opposite ends bent into loops 2.

The upper rung 1 is also made of a single plain rod having loops 2 formed at its outer ends, the terminals of said rod being bent to form 25 downwardly-extending hooks 5. The side pieces each consists of a single length of wire, doubled and bent upon itself to form the central twisted portion 3 and the end loops 4, said loops 4 and the loops 2 formed on the 30 rungs being interlocked, as shown in said drawing.

Having thus described my invention, what I claim is—

The design for a panel for fire-escape ladders substantially as herein shown and described.

In testimony whereof I have hereunto set my hand in presence of two subscribing witnesses.

JAMES C. TATE.
